[57] CLAIM

The ornamental design for a combined power tool carrier and powerboard, as shown and described.

DESCRIPTION

FIG. 1 is a front, top perspective view of the combined power tool carrier and powerboard showing my new design;

FIG. 2 is a rear, bottom perspective view thereof;

FIG. 3 is a left side elevational view thereof; and

FIG. 4 is a top plan view thereof.

The electric cord is shown broken away in FIGS. 2-4 for illustrative purposes only.

FIG. 2.

III-4.

III-3.
